UNITED STATES PATENT OFFICE.

WILLIAM B. MOSES, OF WATERTOWN, MASSACHUSETTS, ASSIGNOR TO GRAY & DAVIS INC., OF CAMBRIDGE, MASSACHUSETTS.

IGNITION APPARATUS.

1,383,229.

Specification of Letters Patent. Patented June 28, 1921.

Application filed April 8, 1918. Serial No. 227,184.

To all whom it may concern:

Be it known that I, WILLIAM B. MOSES, a citizen of the United States, residing at Watertown, in the county of Middlesex and 5 State of Massachusetts, have invented certain new and useful Improvements in Ignition Apparatus, of which the following is a full, clear, and exact specification.

This invention relates to ignition apparatus and with regard to certain more specific 10 features thereof to interrupter and distributor devices particularly adapted for use with multi-cylinder internal combustion engines.

One of the objects of the present invention 15 is to provide simple and reliably operative means for insuring adequate sparking in the engine cylinders at any of the possible engine speeds.

Other objects will be in part obvious and 20 in part pointed out hereinafter.

The invention accordingly consists of the various features of construction, combination 25 of elements and arrangements of parts which will be exemplified by the construction hereinafter set forth and the scope of the application of which will be indicated in the following claims.

In the drawings wherein is shown one of 30 various possible embodiments of the invention—

Figure 1. is a view in vertical central section through a breaker-distributer comprising features of the invention.

Fig. 2. is a plan view of the breaker 35 mechanism, the distributer cap and arm being removed.

Fig. 3. is a plan view of the centrifugal device which governs the position of one of the breaker cams, the breakers and their 40 supporting plates being removed.

Fig. 4. is a sectional view of one of the supporting plates and its associated breaker mechanism.

Referring now more particularly to the 45 drawings there is indicated at 1 a goblet shaped housing having a stem 2 which serves as a journal for a vertical work shaft 3, and having a bowl 4 within which the centrifugal controlling device and the breaker mechanism are arranged. The shaft 50 3 is driven in timed relation to the engine crank shaft and fixed upon the shaft 3 for rotation therewith are the spider 5 and the actuating cam 6. The spider carries pivotally mounted thereon the arms 7 and 8, the

pivots being shown at 9 and 10 in Fig. 3, and the opposite ends of these arms are held normally inward by a spring and link connection indicated at 11. A cam carrying strap 12 of thin sheet metal has an upper flat face against which a cam 13 is secured. The actuating shaft 3 loosely penetrates this strap and cam, and the strap is bent downwardly at opposite sides of the shaft and then outwardly in the form of flat radially extending arms. Contractile springs 15 and 16 respectively connect an end 17 of each of said arms to substantially diametrically opposed arms 18 and 19 of the spider 5. Each arm end 17 is pivotally connected by a link 20 to the yielding ends of the centrifugal arms 7 and 8 respectively. The arms 7 and 8 carry fixed pins 21 depending in arcuate slots 22 formed in the spider 5, the same serving to limit the outward movement of the arms. It will be obvious from the foregoing that should the shaft 3 be rotated at high speed the arms 7 and 8 would move outwardly around their pivotal mountings 9 and 10 and against the influence of the springs 15 and 16. This would cause a variation in the angular relationship between the spider and the cam 13 for a purpose which will more clearly hereinafter appear.

The centrifugal governing device having been described reference will now be had to the interrupter or breaker mechanism. It will be noted that the bowl 4 about midway up is provided with a pair of spaced horizontal ledges 30. These serve respectively as locating means for a pair of separate breaker-supporting plates 31 and 32, the plate 31 being mounted upon the lower ledge by means of screws 33, and the plate 32 being mounted upon the upper ledge by means of screws 34. A slight range of relative angular adjustment is permitted between the plates by means of the slots 35 and the said screws 34.

Each supporting plate has a breaker mechanism thereon and as both are substantially identical a description of one will suffice. The plate 32 for instance has an upstanding portion 40 turned inwardly at 41 forming an ear 42 between which and the plate proper a contact-carrying arm or member 43 is pivotally located. The portion 41 has also a downwardly extending arm 44 to which is secured a spring finger rebound

device 45 which serves to counteract the influence of the actuating shock. The finger is positioned to be in position slightly away from a roller 46 carried by the arm 43 and is effective when the carrying arm is thrown out by the actuating portions of the cam 6. The momentum of the arm due to the shock of actuation tends to throw the roller 46 out of contact with the actuating dwell 10 whereupon the spring finger 45 acts as a resilient limiting stop and return device.

The contact carrying arm is of sheet metal of electrical conductivity and is forked to straddle the cam-roller 46. The sides 50 merge at the free end of the arm and a contact point 51 of platinum alloy or the like is carried at the junction. This contact is known as the "movable contact" distinguished from the "fixed contact" 52 with which it co-operates and which is carried by a block 53 fixed upon the plate 32. A leaf spring 54 has one end bearing against the upstanding portion 40, its body curved around the pivot post of the carrying arm 25 and its other end brought in around and secured to a pin 56 extending between the tines. The tendency of this spring is to yieldingly press the arm 43 to a position of contacting engagement.

30 By the use of two interrupter mechanisms and with the parts positioned as shown a single rotation of the work shaft will produce twelve breaks in the primary circuit, using only a six point cam. It will be noted 35 that the cam 6 has six equi-spaced high portions 60 having short actuating dwells. These portions act to successively engage the cam rollers and open the contact sets of the breaker mechanism. Upon inspection 40 of Fig. 2 of the drawings it will be obvious that the contact carrying arms are arranged to be alternately actuated, that is, first one contact set is opened by a cam portion 60 and then spring closed and subsequently the 45 other set is opened by another cam portion 60.

Primary circuit terminals are indicated at 70 and 71 and the current flow with the circuit closed through the primary coil is from 50 terminal 70 through conductor 73, spring 54, carrying arm 43, contact points 50 and 51, conductor 74, spring 54 of the second breaker mechanism, arm 43, points 51 and 52, all of the second breaker mechanism, 55 conductor 75 to terminal 71. Thus it will be seen that the contact sets are in series arrangement in the primary circuit.

The cam 13 is similar in shape and dimensions to the cam 6 but the former is positioned on its supporting straps so that under conditions of low engine speeds the high portions 80 thereof are slightly staggered relatively to the portions 60 of cam 6. As the cam rollers of the breaker mechanisms 65 extend opposite both cams they are held in

open contact positions by the composite actuating dwell. This, of course, shortens the distance through which the shaft turns with both contact sets closed, but at low engine speeds with the shaft turning comparatively 70 slow the time element is sufficient to allow adequate saturation of the primary coil without choking. As the engine ranges to its higher speeds the increase in speed of the shaft is compensated for by shortening the 75 composite actuating dwell until the high portions 60 and 80 align at very high speeds. This is effected by the centrifugal device hereinbefore described, and as the shaft speed increases the closure range between 80 actuating portions of the cams increases.

The distributing device comprises an arm 90 mounted for rotation with the shaft 3 at the top, and carrying a contact 91 adapted to co-operate successively with a plurality of 85 secondary circuit contacts 92 arranged in an annular row in a distributor head or cap 93 of bakelite or other suitable insulating material. The common high tension contact is shown at 94 and is connected electrically to the contact 91 by a brush 95.

Inasmuch as the two breakers of the interrupter mechanism are mounted respectively on separate plates, the screw and slot securing means of one plate provides for 95 relative adjustment of the breakers so that they may be properly timed.

As many changes could be made in the above construction and as many apparently widely different embodiments of the invention could be made without departing from the scope thereof, it is intended that all matter set forth in the foregoing description or shown in the accompanying drawings shall be interpreted as illustrative and not in a 100 limiting sense.

What I claim is:—

1. In ignition apparatus, in combination, a pair of primary circuit interrupter devices, each of said pair comprising a fixed 110 and a movable contact member, supporting means for one of said pair, and supporting means for the other of said pair comprising means providing for relative adjustment between the supporting means and 115 providing for the securing of same in adjusted position.

2. In ignition apparatus, in combination, a pair of primary circuit contact sets, each set comprising two contacts relatively movable into and out of engagement, a plate upon which one set is mounted, another plate upon which the other set is mounted, and means providing for relative adjustment between the plates and providing for 120 the securing of same in different adjusted positions.

3. In ignition apparatus, in combination, a casing, a support mounted in the casing, a contact set comprising a fixed and mov- 130

able contact, said set being arranged in said support, a second support mounted in said casing, a second contact set comprising a fixed and movable contact, said second set being arranged on said second support, and means having provision for the relative adjustment of said supports and the securing of same in relatively adjusted positions.

4. In ignition apparatus, in combination, 10 a casing, a support mounted in the casing, a contact set comprising a fixed and movable contact, said set being arranged in said support, a second support mounted in said casing, a second contact set comprising a 15 fixed and movable contact, said second set being arranged on said second support, and means having provision for the relative adjustment of said supports and the securing of same in relatively adjusted positions, said 20 casing serving in part as a means for guiding one of said supports in the adjusting operation.

5. In ignition apparatus, in combination, 25 a casing, a support mounted in the casing, a contact set comprising a fixed and movable contact, said set being arranged on said support, a second support mounted in said casing, a second contact set comprising a fixed and movable contact, said second set being arranged on said second support, means having provision for the relative adjustment of said supports and the securing of same in relatively adjusted positions, and a rotatable shaft penetrating 30 the casing between said supports and having means for actuating said contact sets.

6. In ignition apparatus, in combination, 35 a casing, a support mounted in the casing, a contact set comprising a fixed and movable contact, said set being arranged on said support, a second support mounted in said casing, a second contact set comprising a fixed and movable contact, said second set being arranged on said second support, means having provision for the relative adjustment of said supports and the securing of same in relatively adjusted positions, and a rotatable shaft penetrating the casing between said supports and having means for 40 periodically and alternately actuating said contact sets.

7. In ignition apparatus, in combination, 45 a casing, a support mounted in the casing, a contact set comprising a fixed and movable contact, said set being arranged on said support, a second support mounted in said casing, a second contact set comprising a fixed and movable contact, said second set being arranged on said second support, means having provision for the relative adjustment of said supports and the securing of same in relatively adjusted positions, a rotatable shaft penetrating the casing between said supports and having means for 50 periodically and alternately actuating said contact sets.

contact sets, and means adapted automatically to vary the effective length of said actuating means.

8. In ignition apparatus having a primary circuit for internal combustion engines, in combination, a casing, a contact set therein comprising a fixed contact and a movable contact, means adapted to be driven from the engine for intermittently acting on the movable contact to open said circuit and comprising means controlled by varying engine speeds for varying the inactive distance between said first means.

9. In ignition apparatus for internal combustion engines, in combination, a contact set comprising a fixed and a movable contact, a rotatable shaft, movable-contact actuating means carried by said shaft comprising spaced variable length actuator portions, and speed responsive means for varying the length of said actuator portions to decrease or increase the distance between them.

10. In ignition apparatus for internal combustion engines, in combination, a contact set comprising a fixed and a movable contact, a rotatable shaft, movable-contact actuating means carried by said shaft comprising a pair of cam members each having peripherally spaced actuating portions, one of said cam members being driven directly from said shaft and the other of said cam members being driven therefrom through a speed responsive device, and said speed responsive device.

11. In ignition apparatus, in combination, 100 a pair of circuit breakers arranged in series in a primary circuit, a casing, housing and supporting said pair, a shaft journaled in said casing, a centrifugal device operated from said shaft, a cam connected to said 105 centrifugal device and having a plurality of spaced actuating wipers, a second cam driven directly from said shaft, arranged adjacent said first cam and having a plurality of spaced actuating wipers which at low 110 shaft speeds are staggered to act with the wipers of the first cam to elongate the actuating dwell, said centrifugal device acting at the higher shaft speeds to cause relative movement between the cams to shorten the 115 dwell.

12. In ignition apparatus, in combination, 120 a pair of circuit breakers arranged in series in a primary circuit, a casing, housing and supporting said pair, a shaft journaled in said casing, a centrifugal device operated from said shaft, a cam connected to said 125 centrifugal device and having a plurality of spaced actuating wipers, a second cam driven directly from said shaft, arranged adjacent said first cam and having a plurality of spaced actuating wipers which at low shaft speeds are staggered to act with the wipers of the first cam to elongate the actuating dwell, said centrifugal device act- 130

ing at the higher shaft speeds to cause relative movement between the cams to shorten the dwell, and means for limiting the action of said centrifugal device when the wipers 5 are substantially aligned.

13. In an ignition device for internal combustion engines, in combination, a breaker adapted to be included in a primary circuit and comprising a pair of relatively engageable and disengageable contacts, spring means tending to cause engagement of said contacts, spaced means acting in opposition to said spring means adapted to disengage said contacts periodically, and means adapted automatically to increase the distance between said spaced means as the engine speed increases.

14. In an ignition device for internal combustion engines, in combination, a breaker 20 adapted to be included in a primary circuit and comprising a pair of relatively engageable and disengageable contacts, spring means tending to cause engagement of said contacts, spaced means acting in opposition 25 to said spring means adapted to disengage said contacts periodically, means adapted automatically to increase the distance between said last means as the engine speed increases, and a distributing device comprising a multiplicity of fixed contacts and a movable contact movable in timed relation with said disengaging means.

15. In an ignition device for internal

combustion engines, in combination, a breaker adapted to be included in a primary circuit and comprising a pair of relatively engageable and disengageable contacts, spring means tending to cause engagement of said contacts, spaced means acting in opposition to said spring means adapted to disengage said contacts periodically, means adapted automatically to increase the distance between said last means as the engine speed increases without varying the "time" of contact disengaging relatively to the engine, and a distributing device comprising a multiplicity of fixed contacts and a movable contact movable in timed relation with said disengaging means.

16. In an ignition device, in combination, 50 a casing, a rotatable shaft journaled therein, a plate rotatable with said shaft, arms pivotally mounted on said plate, springs for yieldingly holding said arms against the action of centrifugal force, a set of breaker contacts, an actuator driven from said shaft comprising spaced-portions for periodically opening the breaker contacts and holding them open for a limited time, a member connected to the swinging ends of said pivotally mounted arms, said member having spaced high portions adapted to lag slightly behind the high portions of the actuator to form a composite dwell.

WILLIAM B. MOSES.
